CLAIM

The ornamental design for a folding knife as shown and described.

DESCRIPTION

FIG. 1 is a front perspective view from above of the claimed design;

FIG. 2 is a left side view of the claimed design of FIG. 1;

FIG. 3 is a right side view of the claimed design of FIG. 1;

FIG. 4 is a front view of the claimed design of FIG. 1;

FIG. 5 is a rear view of the claimed design of FIG. 1;

FIG. 6 is a top view of the claimed design of FIG. 1;

FIG. 7 is a bottom view of the claimed design of FIG. 1; and

FIG. 8 is a left view of the claimed design of FIG. 1 in a second arrangement; and,

FIG. 9 is a right-side view of the claimed design of FIG. 1 in the second arrangement.

Any portion of the article depicted in broken lines forms no part of the claimed design.

1 Claim, 5 Drawing Sheets(56)
